FIBER CLEANING

George S. Rippey, Boston, Mass., assignor to
 United Fruit Company, Boston, Mass., a corpora-
 tion of New Jersey

Application April 12, 1939, Serial No. 267,428

23 Claims. (Cl. 19—7)

This invention relates to a process of preparing long vegetable fibers for market, and more specifically to the step of stripping the desired fibers of pulpy and other undesired material included in the natural content of a unit of raw vegetable matter which contains the desired fibers.

While my invention has been found especially suitable in the preparation of "manila" fiber for market, the process is equally adapted for use in the treatment of similar fibers present in other types of natural vegetable matter, for instance, sisal, ramie, and maguey, and in the treatment of fibers generally of the class which are found in natural leaves or stalks in substantially parallel relation and are commonly referred to as fibro-vascular bundles, each consisting of individual fiber-cells which overlap at their ends to form compositely a fiber of considerable length.

One of the well known fibers of this class is "manila" fiber, obtained from the stalks of the abaca plant, cultivated extensively in the Philippines. The nature of the abaca plant, and the distribution of fibers therein, is well known to those acquainted with the industry, and reference is made to the description thereof contained in Bulletin No. 1 of the Fiber Standardization Board of the Department of Agriculture and Natural Resources of the Government of the Philippine Islands, entitled "The Standard Grades of Abaca," by M. M. Saleby, Manila, Bureau of Printing, 1930. As therein fully described, the commercially desirable fibers are found in the leaf sheaths which form the stalk of the plant. The stalk is botanically known as a "false stalk," because it comprises, in the fully grown plant, merely a group of overlapping crescent-shaped sheaths laid tightly one upon another over a central core. Each leaf sheath contains the fibers extending substantially parallel to each other longitudinally of the sheath along its natural exterior section. The remainder of the sheath is made up of fiberless tissues, and other fine fibers of a tensile strength weaker than that required for commercial use, all of which must be separated or stripped from the desired fibers in preparing them for market. This operation is known as, and will be hereinafter referred to as, the cleaning operation.

Since the grade of the fiber, and therefore, to a great extent, its value, depends upon the excellence of the cleaning operation, it has been evident that a method which could guarantee a uniform and excellent cleaning would be of inestimable value to the art. Present day cleaning opera-

tions are not uniformly satisfactory, and the amount of fiber prevalent that is of lower grades entirely because of the poor quality of the cleaning operation, is considered unnecessarily high by those interested in the welfare of the industry, and results in proportionately unnecessary higher prices for the best grades.

One commonly used method of cleaning the fiber of the abaca plant involves a scraping operation of the exterior section of the leaf sheath (known as a "tuxy") by passing it under a rigid blade spring- or weight-pressed against a fixed block. This scraping operation is satisfactory in producing "excellent grade" fiber, if performed uniformly, but uniform scraping requires constant care on the part of the operator and constant adjustment of the scraping apparatus, with resulting sacrifice in speed. Since the scraping operation is generally done in the field with extremely crude apparatus, the required care is the exception rather than the rule, and quantities of fiber which would be excellent grade if properly cleaned, must be graded in inferior classes, due to careless or non-uniform cleaning. Additionally, the preparation of a "tuxy" for the cleaning step necessitates an extra operation.

Another form of cleaning involves a mechanical beating of the leaf sheath. Any such beating has the insurmountable drawbacks of tending to rupture the larger fibers by too great pressure, and to leave the smaller and weaker fibers untouched, passing them along with the desired strong fibers although not properly cleaned. Inclusion of weak fibers in the output, lessening the average fiber strength, is in and of itself undesirable, and, when not even properly cleaned, appreciably lowers the quality of the yield.

A primary object of my invention is therefore a higher yield of "excellent grade" fiber from potentially "excellent grade" fiber sheaths through utilization of a uniformly excellent cleaning operation.

My invention is directed broadly to the stripping, cleaning, or separating of long vegetable fibers of the class described, by subjecting the surface of a unit of vegetable matter containing the fibers to the impact of a liquid stream of such force that the fibers are fully cleaned, and also, if desired, the smaller, weak, undesired fibers, are completely stripped or broken away. In the practice of my invention, the operation of "tuxying," prerequisite to the scraping type of cleaning, is unnecessary, since the natural unit thickness can be handled in one cleaning operation and the fibers of an entire leaf sheath may, if desired, be

properly cleaned in one operation. Likewise in cleaning in accordance with my invention, rupture or other injury to the large fibers, encountered in carrying out a mechanical beating operation is entirely avoided, and weak fibers can be separated along with the mass of fiberless tissue, from the desired fibers.

Further features and objects of my invention will be apparent from the accompanying description which includes reference to a preferred type of machine which I use in connection with the practice of the process of my invention, which machine is more fully disclosed in an application filed simultaneously herewith.

15 In the accompanying drawings:

Fig. 1 is a representation of a stalk of the abaca plant;

Fig. 2 is a cross-section of the stalk along the lines 2—2 of Fig. 1;

20 Fig. 3 is an enlarged cross-section of one of the individual leaf sheaths shown in Fig. 2;

Fig. 4 is a diagrammatic representation of a leaf sheath passing through a rolling mill;

Fig. 5 is a perspective diagrammatic view, with 25 parts broken away, of a machine adapted for use in connection with the cleaning step in my process; and

Fig. 6 is a plan view of the operating wheel in a different position than that shown in Fig. 5;

30 Fig. 7 is an enlarged cross-section of a portion of the wheel in still a different position; and

Fig. 8 is a diagrammatic elevation of the operating wheel.

As shown in Figs. 1-3, the stalk 1 of the abaca 35 plant comprises a series of overlapping, crescent-shaped leaf sheaths 2, one of which is shown in cross-section in Fig. 3. The leaf sheaths 2 are distributed in the stalk in the fully grown plant, about a central core 3, as shown in Fig. 2.

40 After the plant has been cut down and the stalk cut transversely to a predetermined suitable length, I separate the desired leaf sheaths from each other and from the core 3, either manually, as in former practice, or in accordance with a 45 centrifugal mechanical operation described in an application co-pending herewith, Serial No. 270,504, filed April 28, 1939.

I next flatten each unit, preferably by passing it through a roller mill, as diagrammatically 50 illustrated in Fig. 4. A roller pressure of approximately 2000 lbs. is suitable.

The cleaning step is then performed to separate and clean the individual desired fibers which run along the natural exterior section of the unit 55 from the pulpy fiberless tissue contained in the interior section of the natural unit. My cleaning step is performed preferably by anchoring one end of the flattened unit, and then directing a transverse stream of water, having a velocity 60 head in excess of 500 lbs. per square inch, against an exposed surface, preferably the natural exterior hard surface, of the unit, and passing the stream progressively, and preferably in uniform progression, longitudinally of the unit and away 65 from the anchored end thereof only, while supporting the portion of the unit being operated upon against a supporting surface or baffle.

In order to permit continuous operation, I prefer to advance the flattened units, one after another in edge to edge relationship, and transversely of the individual fibers, towards, and in a direction transverse to, the path of movement of the impact point of a stream of water, which impact point has a relative cyclical movement 70 across a baffle.

An illustration of my method may be understood by reference to Figs. 5, 6 and 7. Fig. 5 illustrates diagrammatically the operating elements of my machine, which includes a rotary element E having an orifice 24 in the periphery 5 of a block 21 and positioned radially from the axis of a rotatable shaft 12, on which the wheel E is mounted, a distance for rotation in close proximity to a substantially cylindrical stationary baffle 10 co-axial with shaft 12, and forming 10 a top surface of the frame 8 of the machine. The wheel E is adapted for rotation at a constant speed in a counterclockwise direction, as viewed in Fig. 5 and orifice 24 passes progressively at a uniform speed across baffle 10 in each 15 revolution of the wheel E.

As shown in Fig. 7, for convenience, orifice 24 is formed by walls of block 21 which are at an angle of approximately 70° to the perpendicular to the tangential plane of the baffle 10, at a particular point across which the orifice is passing. The angle of inclination of the water on the baffle 10 is therefore approximately 20°.

Such construction of the orifice directs the water onto the baffle 10 so that it flows therealong 25 and curvingly upwardly so that it is ejected at the near end of the baffle 10, as seen in Fig. 5, upwardly into a suitable hood 68, which directs the water to a waste line.

For the purpose of advancing the units continuously, I provide a horizontal conveyer A, 30 passing around a roller 70, on which the flattened units may be placed cross-wise in edge to edge relationship, with their exterior hard surfaces disposed upwardly, and with one end thereof overhanging the conveyer. This conveyer A advances the unit towards the wheel E, so that one end passes onto an auxiliary conveyer C advancing in the same direction and the opposite overhanging end is gripped by a feed mechanism B, comprising any suitable endless frictional retaining means having a cooperating traverse in a direction substantially parallel to the axis of shaft 12. The feed mechanism B is adapted to grip the ends of the units successively and to advance them at a substantially continuous speed 40 toward and beyond the path of the wheel E.

A guide 35, shown in Figs. 5, 6 and 8, on the wheel E, acts to urge the loose ends of the units 45 downwardly against the baffle 10, and into a semi-circular contour, the guide including a peripheral surface spiralling radially inwardly in a counter-clockwise direction, as seen in Figs. 5 and 8, from the orifice 24, and having a circumferential leading edge spiralling axially towards the conveyer A and terminating in a rod 36 extending towards and over conveyer mechanism A. The end of rod 36 is co-axial with shaft 12 and therefore revolves about its center in a horizontal plane spaced from the plane of conveyer A. The guide 35 thus acts to direct the units 50 downwardly between the path of the orifice and the baffle 10, as they are drawn by conveyers B towards the path of rotation of the orifice. It will be understood that as soon as the water is 55 turned on as the orifice commences its passage across baffle 10, the stream will pass continuously across the baffle into hood 68. The loose end of a width of fed material will therefore be straightened across the baffle by the flow of water, the instant the gripped end is subjected to the impact.

Since, as shown in Fig. 6, the orifice 24 is of limited axial length, I prefer to have my feed mechanism B advance in predetermined timed relation with the rotation of shaft 12, so that a 70 75

width of material equal to the over-all axial length of the orifice 24 will be advanced by feed mechanism B with each revolution of the wheel E.

5 In order to accommodate the continuous advance of the strips by the feed mechanism B during the passage of orifice 24 across baffle without permitting the escape of the cleaned section of the unit from beneath wheel E, I provide a follower 30, which comprises a substantially cylindrical surface extending throughout an arc of 180° in the opposite direction from the guide 35, and this follower has a leading circumferential edge spiralling in the opposite axial direction from the axial spiral of the guide 35. The offset is equal to $\frac{1}{2}$ the axial over-all width of the orifice 24. The other 180° arc of the wheel E is reinforced by a plate 34.

10 The block 21 on wheel E has a series of peripherally extending and radially outstanding parallel teeth 41, which are positioned just following the orifice 24, as indicated by the parallel lines in Fig. 6. These teeth are designed to act as a comb to hold the cleaned portion of the fibers 15 progressively down against the baffle 10 during the traverse of the orifice across the fed material. As shown in Fig. 6, the cylindrical surface or follower 30 extends from a point just following the teeth 41.

15 In order to keep the material from wrapping around or becoming entangled with the shaft 12 after passing from beneath the path of the follower 30, I provide a series of axially extending pins 42, fixed to the plate 34 which act to keep 20 the fibers away from the wheel E until they have passed well beyond its path of rotation.

25 In order also to separate the material being operated on by wheel E in one revolution from that which will be subsequently operated on in the next revolution, I mount a cutter 40, extending through guide 35 on the wheel E, which cooperates with baffle 10 to cut a width of the fed material determined by the relative speeds of feed mechanism B and wheel E, with each revolution, the cutting edge being mounted substantially in a vertical plane with the leading circumferential edge of the orifice 24. When these 30 speeds are synchronized to cause the advance of a width of material equal to the over-all axial dimension of the orifice 24 with each revolution of shaft 12, it will be seen that cutter 40 will sever successive widths which will be subjected in their entirety to the stream passing from orifice 24 during the passage of the orifice across the baffle 35 in successive revolutions.

35 Liquid, preferably water, may be supplied to the orifice 24 in any suitable manner. I have illustrated in Fig. 6 a construction which is disclosed more fully in my co-pending application, filed simultaneously herewith, including a recess 50 in the shaft 12, connected at the butt end of shaft 12 with the block 21 by a pipe and suitable connections indicated at 51 in Fig. 5. The water may be supplied to the hollow recess 50 through a suitable inlet housing 52, from a pipe 55 shown in Fig. 5.

40 Preferably the water is supplied to the inlet 52 intermittently, so that it will issue from the orifice 24 only during that portion of revolution of wheel E during which orifice 24 is adjacent the baffle 10. This intermittent supply may be provided by any one of several expedients, one of which is described fully in my application previously referred to filed simultaneously herewith.

45 Flattened abaca leaf sheath units have been

successfully and excellently cleaned by one passage through this machine, when the water supplied to the outlet 52 has a velocity head of 2500 lbs. per square inch. In a wheel E, having an orifice which moves in a path having a diameter 5 of approximately 43 inches, I have provided an orifice having the dimensions of 6 inches in axial length and approximately .010 of an inch in width. The orifice 24 clears baffle 10 by approximately $\frac{1}{2}$ inch, and the follower 30 clears 10 the baffle by about $\frac{1}{2}$ inch. Since the fibers run generally between .002 and .010 of an inch in diameter, it will be seen that there is no scraping action by the orifice. My process has been performed with the units advancing at a rate of 20 15 feet per minute, with shaft 12 and orifice 24 revolving at the rate of 40 R. P. M.

20 Since, with a pressure of 2500 lbs. per square inch, and with an orifice of the dimensions given, the stream of water issuing from the orifice 24 20 will have a velocity of approximately 600 feet per second, it will be seen that the stream of water is a continuous thin dense blade-like jet which acts somewhat as a rigid transverse blade scraping the strip of material. However, since 25 the hydraulic blade is not actually rigid, its impact plane varies according to the particular configuration of the surface of the material on which it is acting, and therefore, it does not rupture the larger fibers. With the static and ve 30 locity head at approximately 2500 lbs. per square inch, and with what has been termed the angle of inclination of 20°, the force of impact will be 35 5000 lbs. per square inch, and the normal component of that force of impact on the strip material will be approximately 1710 lbs. This normal component of the force of impact I find to be perfectly suitable for cleaning abaca leaf sheaths completely by one passage through my apparatus. 40

45 Since the static head pressure, the dimensions of the orifice 24, and the angle of inclination of the stream are all variables which may be changed, the particular pressure and dimensions described are merely by way of example. In order, however, to secure suitable cleaning, the normal component of the force of impact on the fed material should be something in excess of approximately 1000 lbs. A suitable range for the 50 velocity head, which can be mentioned, is between 1500 and 3000 lbs. per square inch, and a suitable range for the normal component of the force of impact on the sheath unit is between approximately 1000 lbs. and 2000 lbs. Depending upon the particular pressure used a greater 55 or less amount of the weaker fibers will be broken by the impact and carried away by the water along with other pulpy material.

55 The conveyor mechanism B carries the units beyond the path of rotation of wheel E, and the uncleaned gripped ends may then be severed from the cleaned fibers, which are separated from one another, and which, after drying, are in substantially proper condition for marketing. 60

I claim:

1. In the process of preparing long vegetable fibers for market, the steps which comprise separating a unit of vegetable matter containing the desired fibers disposed substantially parallel to each other from the rest of the plant, substantially flattening the unit, advancing the unit in a direction transversely of the individual fibers towards a cutter, anchoring an end of the advancing unit, cutting a predetermined width of the anchored unit from the remainder, and sub- 65 70 75

jecting a predetermined portion of an exposed surface of the individual cut width in uniform progression in a direction transverse to the direction of advance and longitudinally of said fibers 5 away from said anchored end, to the continuous impact of a fluid stream, while progressively supporting the individual cut width at the successive points of impact against a substantially continuous stationary supporting surface.

10 2. In the process of preparing long vegetable fibers for market, the steps which comprise separating units of vegetable matter containing the desired fibers disposed substantially parallel to each other from the rest of the plant and from 15 each other, substantially flattening the units, advancing the units continuously in edge to edge relation in a direction transversely of the individual fibers towards a cutter, successively anchoring ends of the advancing units, successively 20 cutting a predetermined width of material from the advancing anchored units and successively subjecting a predetermined portion of an exposed surface of the successive individual cut widths each in uniform progression in a direction trans- 25 verse to the direction of advance and longitudinally of said fibers away from said anchored end, to the continuous impact of a fluid stream while progressively supporting each individual cut width at the successive points of impact against 30 a substantially continuous stationary supporting surface.

3. In the process of preparing long vegetable fibers for market, the method of separating and cleaning individual desired fibers from pulpy or other undesired material included in the original content of a unit of vegetable matter containing a plurality of said fibers, which includes the steps of advancing the unit in a direction transversely of the individual fibers, anchoring ends of the individual fibers and subjecting a predetermined portion of the exposed surface of the unit pro- 35 gressively in a direction substantially perpendicular to the direction of advance, to the continuous impact of a fluid stream, thereby stripping the 40 undesired material progressively from the fibers while they are anchored.

4. In the process of preparing long vegetable fibers for market, the method of separating and cleaning individual desired fibers from pulpy or other undesired material included in the original content of a unit of vegetable matter containing a plurality of said fibers disposed substantially parallel to each other, which includes the steps of advancing the unit in a direction transversely 45 of the individual fibers, anchoring one end of the advancing unit and subjecting a predetermined portion of the exposed surface thereof progres- 50 sively in a direction transverse to the direction of advance and longitudinally of said unit away from said anchored end, to the continuous impact of a fluid stream.

5. In the process of preparing long vegetable fibers for market, the method of separating and cleaning individual desired fibers from pulpy or other undesired material included in the original content of units of vegetable matter containing the fibers which includes the steps of advancing the units continuously in edge to edge relation- 55 ship in a direction transversely of the individual fibers, anchoring ends of the advancing units, and successively subjecting a predetermined portion of the exposed surface of each unit progressively in a direction transverse to the direction of ad- 60 vance and longitudinally of each unit away from 65

the anchored end thereof only, to the continuous impact of a fluid stream.

6. In the process of preparing long vegetable fibers for market, the steps which comprise separating a unit of vegetable matter containing the desired fibers from the rest of the plant, substantially flattening the unit, anchoring one end of the unit, advancing the flattened anchored unit in a direction transversely of the fibers to a cutter, cutting a predetermined width of the anchored unit from the remainder, and subjecting a predetermined portion of the surface of the individual cut width to the continuous impact of a fluid stream.

7. In the process of preparing long vegetable fibers for market, the method of separating and cleaning individual desired fibers from pulpy or other undesired material included in the original content of a unit of vegetable matter containing a plurality of said fibers, which includes the steps of advancing the unit in a direction transversely of the individual fibers to a cutter, anchoring one end of the advancing unit, cutting a predetermined width of the anchored unit from the remainder, and subjecting an exposed surface of the cut width progressively to the continuous impact of a fluid stream.

8. In the process of preparing long vegetable fibers for market, the method of separating and cleaning individual desired fibers from pulpy or other undesired material included in the original content of a unit of vegetable matter containing a plurality of said fibers, which includes the steps of advancing the unit in a direction transversely of the individual fibers to a cutter, anchoring one end of the advancing unit, cutting a predetermined width of the anchored unit from the remainder, and subjecting an exposed surface of the cut width progressively in a direction transverse to the direction of advance to the continuous impact of a fluid stream.

9. In the process of preparing vegetable fibers for market, the method of separating and cleaning individual desired fibers from pulpy or other undesired material included in the original content of units of vegetable matter containing the fibers which includes the steps of advancing said units continuously in edge to edge relation to a cutter, anchoring an end of the advancing units, successively cutting a predetermined width of material from the advancing anchored units, and successively subjecting an exposed surface of the successive individual cut widths progressively to the action of a fluid stream.

10. In the process of preparing vegetable fibers for market, the steps which comprise separating units of vegetable matter containing the desired fibers from the remainder of the plant, substantially flattening the units, advancing said flattened units continuously in edge to edge relation in a direction transversely of the individual fibers towards a cutter, anchoring one end of the advancing units, successively cutting a predetermined width of material from the advancing anchored units, and successively subjecting portions of the surface of the successive individual cut widths progressively to the continuous impact of a fluid stream.

11. In the process of preparing vegetable fibers for market, the steps which comprise separating units of vegetable matter containing the desired fibers from the remainder of the plant, substantially flattening the units, advancing said flattened units continuously in edge to edge relation in a direction transversely of the individual fibers,

anchoring one end of the advancing units, and, while the units advance at a uniform speed, successively cutting a predetermined width of material from the advancing anchored units and successively subjecting the surface of the successive individual cut widths progressively to the continuous impact of a fluid stream.

12. In the process of preparing vegetable fibers for market, the steps which comprise separating units of vegetable matter containing the desired fibers from the remainder of the plant, substantially flattening the units, advancing said flattened units continuously in edge to edge relation in a direction transversely of the individual fibers to a cutter, anchoring one end of the advancing units, successively cutting a predetermined width of material from the advancing anchored units, and successively subjecting the surface of the successive individual widths as they are cut, progressively to the continuous impact of a fluid stream.

13. The process of extracting long vegetable fibers from a unit of vegetable matter containing a plurality of desired fibers naturally bonded to each other in substantially parallel relation in said unit, and simultaneously cleaning said fibers of pulpy or other undesired material adherent to said fibers and included in the original content of the unit, which includes the step of subjecting an exposed surface of the unit progressively and longitudinally of the fibers to the hydraulic scraping action of a continuous thin dense blade-like jet of liquid having a velocity head at the point of impact on the unit in excess of 500 lbs. per square inch, while maintaining both the portions of the fibers to be cleaned and the cleaned portions of the fibers in their natural substantially parallel relation and supporting said unit against the force of impact of said jet.

14. The process of extracting long vegetable fibers from a unit of vegetable matter containing a plurality of desired fibers naturally bonded to each other in substantially parallel relation in said unit, and simultaneously cleaning said fibers of pulpy or other undesired material adherent to said fibers and included in the original content of the unit, which includes the step of subjecting an exposed surface of the unit progressively and longitudinally of the fibers to the hydraulic scraping action of a continuous thin dense blade-like jet of fluid having a force of impact on the unit, the normal component of which is in excess of 1000 lbs., while maintaining the portions of the fibers to be cleaned in their natural substantially parallel relation and supporting said unit against the force of impact of said jet.

15. The process of extracting long manila fibers directly from a leaf sheath unit of the abaca plant and simultaneously separating and cleaning said fibers which consists in flattening a leaf sheath unit thereof and then, while maintaining both the portions of the fibers to be cleaned and the cleaned portions of the fibers in their natural substantially parallel relation, uniformly subjecting an exposed surface of the flattened unit progressively and longitudinally of the fibers to the hydraulic scraping action of a continuous thin dense blade-like jet of liquid having a velocity head at the point of impact on the sheath of the order of 2000 to 3000 lbs. per square inch, while supporting said unit against the force of impact of said jet, thereby initially freeing the fibers from pulpy and other undesired material originally adherent thereto as part of the natural content of the unit and simultaneously separating the

fibers from one another and cleaning said fibers of said undesired material.

16. The process of extracting long manila fibers directly from a leaf sheath unit of the abaca plant and simultaneously separating and cleaning said fibers which consists in flattening a leaf sheath unit thereof and then, while maintaining portions of the fibers to be cleaned in their natural substantially parallel relation, uniformly subjecting an exposed surface of the flattened unit progressively and longitudinally of the fibers to the hydraulic scraping action of a continuous thin dense blade-like jet of liquid having a velocity head at the point of impact on the sheath of the order of 2000 to 3000 lbs. per square inch, while supporting said unit against the force of impact of said jet, thereby initially freeing the fibers from pulpy and other undesired material originally adherent thereto as part of the natural content of the unit and simultaneously separating the fibers from one another and cleaning said fibers of said undesired material.

17. The process of extracting long vegetable fibers from a unit of vegetable matter containing a plurality of desired fibers naturally bonded to each other in substantially parallel relation in said unit, and simultaneously cleaning said fibers of pulpy or other undesired material adherent to said fibers and included in the original content of the unit, which includes the step of subjecting an exposed surface of the unit progressively and longitudinally of the fibers to the hydraulic scraping action of a continuous thin dense blade-like jet of fluid having a velocity head at the point of impact on the unit in excess of 500 lbs. per square inch, while maintaining the opposite surface of the uncleared portion of the unit, as the unit is cleaned, against, and fixed relative to, a substantially continuous supporting surface with the portions of the fibers to be cleaned in their natural substantially parallel relation, thereby supporting said unit against the force of impact of said jet.

18. The process of extracting long vegetable fibers from a unit of vegetable matter containing a plurality of desired fibers naturally bonded to each other in substantially parallel relation in said unit, and simultaneously cleaning said fibers of pulpy or other undesired material adherent to said fibers and included in the original content of the unit, which includes the step of subjecting an exposed surface of the unit progressively and longitudinally of the fibers to the hydraulic scraping action of a continuous thin dense blade-like jet of fluid having a force of impact on the unit, the normal component of which is in excess of 1000 lbs., while maintaining the opposite surface of the uncleared portion of the unit, as the unit is cleaned, against, and fixed relative to, a substantially continuous supporting surface with the portions of the fibers to be cleaned in their natural substantially parallel relation, thereby supporting said unit against the force of impact of said jet.

19. The process of extracting long vegetable fibers from a unit of vegetable matter containing a plurality of desired fibers naturally bonded to each other in substantially parallel relation in said unit, and simultaneously cleaning said fibers of pulpy or other undesired material adherent to said fibers and included in the original content of the unit, which includes the step of subjecting an exposed surface of the unit progressively and longitudinally of the fibers to the hydraulic scraping action of a continuous thin

dense blade-like jet of fluid having a force of impact on the unit, the normal component of which is of the order of 1500 to 2000 lbs., while maintaining the opposite surface of the uncleared portion of the unit, as the unit is cleaned, against, and fixed relative to, a substantially continuous supporting surface with the portions of the fibers to be cleaned in their natural substantially parallel relation, thereby supporting said unit against the force of impact of said jet.

20. The process of extracting long vegetable fibers from a unit of vegetable matter containing a plurality of desired fibers naturally bonded to each other in substantially parallel relation in said unit, and simultaneously cleaning said fibers of pulpy or other undesired material adherent to said fibers and included in the original content of the unit, which includes the step of subjecting an exposed surface of the unit progressively and longitudinally of the fibers to the hydraulic scraping action of a continuous thin dense blade-like jet of fluid having a velocity at the point of impact on the unit in excess of 250 ft. per second, while maintaining the opposite surface of the uncleared portion of the unit, as the unit is cleaned, against, and fixed relative to, a substantially continuous supporting surface with the portions of the fibers to be cleaned in their natural substantially parallel relation, thereby supporting said unit against the force of impact of said jet.

21. The process of extracting long vegetable fibers from a unit of vegetable matter containing a plurality of desired fibers naturally bonded to each other in substantially parallel relation in said unit, and simultaneously cleaning said fibers of pulpy or other undesired material adherent to said fibers and included in the original content of the unit, which includes the steps of anchoring said unit, and subjecting a predetermined portion of an exposed surface thereof progressively in a direction away from the anchorage point only and longitudinally of said

fibers to the scraping action of a continuous thin dense blade-like jet of fluid having a velocity head at the point of impact on the unit in excess of 500 lbs. per square inch, while supporting said unit against the force of impact of said jet. 5

22. The process of extracting long vegetable fibers from a unit of vegetable matter containing a plurality of desired fibers naturally bonded to each other in substantially parallel relation in said unit, and simultaneously cleaning said fibers of pulpy or other undesired material adherent to said fibers and included in the original content of the unit, which includes the steps of anchoring said unit and subjecting a predetermined portion of the natural exterior surface thereof progressively in a direction away from the anchorage point only and longitudinally of said fibers to the scraping action of a continuous thin dense blade-like jet of fluid having a velocity head at the point of impact on the unit 15 in excess of 500 lbs. per square inch, while supporting said unit against the force of impact of said jet. 20

23. The process of extracting long vegetable fibers from a unit of vegetable matter containing a plurality of desired fibers naturally bonded to each other in substantially parallel relation in said unit, and simultaneously cleaning said fibers of pulpy or other undesired material adherent to said fibers and included in the original content of the unit, which includes the steps of anchoring said unit and subjecting a predetermined portion of an exposed surface thereof in uniform progression in a direction away from the anchorage point only and longitudinally of 35 said fibers to the scraping action of a continuous thin dense blade-like jet of fluid having a velocity head at the point of impact on the unit in excess of 500 lbs. per square inch, while supporting said unit against the force of impact of 40 said jet. 30

GEORGE S. RIPPEY.
